UNITED STATES PATENT OFFICE.

HEINRICH GEORG LEICHTWEISS, OF DARMSTADT, GERMANY, ASSIGNOR TO GANDEN-BERGER'SCHE MASCHINENFABRIK, GEORG GOEBEL, OF DARMSTADT, GERMANY, A CORPORATION OF GERMANY.

INKING MECHANISM FOR PLATEN PRINTING PRESSES.

Application filed December 8, 1925, Serial No. 74,096, and in Germany December 9, 1924.

It has been proposed in inking mechanisms for platen printing presses to move the distributing rollers in a closed path whether moved as a carriage or by a chain 5 or in the circuit on the printing stock or form. The known devices for this purpose have however the fundamental disadvantage that their sphere of action is not sufficiently free.

10 According to the invention the distributing rollers rest in rings laterally arranged on the printing press frame, supported by antifriction rollers and rotated by the machine. Through the open apertures of these 15 rings runs the strip of paper to be printed upon. There are no spokes or other members to obstruct the space. The two rings are connected with one another by stiffening members and the latter serve in a further 20 development of the invention as carriers for the axially displaceable supporting bodies of the distributing rollers.

The accompanying drawing diagrammatically illustrates by way of example one constructional form of the invention, wherein—

Fig. 1 is a longitudinal section through a platen printing press,

Fig. 2 a cross-section and

Fig. 3 the arrangement of the distributing rollers in a roller frame.

Over the printing table or platen 1 of a head printing press is guided in a known manner the strip of paper or the like 2 to be printed upon. The printing stocks or 35 forms 3 are suspended in the printing head 4. The latter is moved up and down in the direction of the double-headed arrow 7 by means of two cranks 17 mounted on the main driving shaft 16 through the medium of 40 connecting rods 5, which are pivoted to two draw-rods 6.

When the printing head 4 is in its highest position the inking of the forms 3 is effected by the group of distributing rollers 8. In 45 order that the distributing rollers 8 may be able to adapt their main circulating movement determined by the roller frame 12 during the inking of the forms 3 to the plane of the forms they are resiliently supported.

50 The roller-carriers 9 are mounted as shown in Fig. 3 in such a way as to be transversely displaceable in clamps 10 in which they can be clamped by means of set screws 11 and can be laterally adjusted in such a way that

their position corresponds to the position of 55 the forms 3 in the printing head 4. The setting or adjusting clamps 10 are rigidly connected with the two rings 12 which are arranged in vertical planes at the sides of the frame walls of the printing press. The 60 clamps 10 serve at the same time for the stiffening of the roller frame thus constructed.

The rings 12 hang in carrying rollers 13 which are journaled on bolts 14 rigidly connected with the machine frame. The rings 12 are formed with external teeth in which two toothed wheels 15 engage. The latter are rigidly mounted on the main driving shaft 16. When the shaft 16 rotates, the 70 rings 12 with their clamps 10 are therefore set in rotation, and with them the roller-carriers 9, together with the distributing rollers 8, either uniformly, or, by means not here illustrated, non-uniformly, in which 75 case the distributing rollers 8 roll over the ink-supplying roller 18 for the purpose of taking ink therefrom.

The arrangement is so designed that the 80 distributing rollers 8, when the forms 3 come into contact with the strip of paper or the like 2 to be printed upon, are located outside the range of movement of the forms.

In order that the roller frame 12 may run at a low speed a plurality of groups of 85 distributing rollers may be journaled in one roller frame 12. The arrangement is then so designed that one of the groups of distributing rollers is always ready for inking when the form 3 rises. Fig. 2 shows by way 90 of example a roller frame with two groups of rollers.

The roller frame 12 may also be so arranged as to move round the printing head 4 instead of as illustrated in Figs. 1 and 2. 95

In order to enable rather long printing tables supported at a number of points to be obtained for use with a large-sized paper and numerous forms a plurality of roller frames located side by side may be employed 100 as indicated in Fig. 1.

What I claim is:—

1. Inking mechanism for platen printing presses, comprising a printing press frame, antifriction rollers mounted laterally on said frame, rings supported by said antifriction rollers, in such a position that the paper to be printed upon can pass through the central 105

apertures thereof, driving means for rotating said rings, and ink distributing rollers mounted in said rings and adapted to move therewith in a circular path.

5. Inking mechanism for platen printing presses, comprising a printing press frame, antifriction rollers mounted laterally on said frame, rings supported by said antifriction rollers, in such a position that the paper to be printed upon can pass through the central apertures thereof, longitudinal stiffening stays rigidly connecting said rings with one another, driving means for rotating said rings, and ink distributing rollers mounted in said rings and adapted to move therewith in a circular path.

3. Inking mechanism for platen printing presses, comprising a printing press frame, antifriction rollers mounted laterally on said frame, rings supported by said antifriction rollers, in such a position that the paper to be printed upon can pass through the central apertures thereof, longitudinal stiffening stays rigidly connecting said rings with one

another, bearings longitudinally displaceable on said stays, driving means for rotating said rings, and ink distributing rollers journaled in said bearings and adapted to move therewith in a circular path.

4. Inking mechanism for platen printing presses, comprising a printing press frame, antifriction rollers mounted laterally on said frame, rings supported by said antifriction rollers in such a position that the paper to be printed upon can pass through the central apertures thereof, longitudinal stiffening stays rigidly connecting said rings with one another, adjustable clamps longitudinally displaceable on said stays, levers mounted on said clamps, ink distributing rollers journaled on said levers, springs acting on said levers and tending to press said ink distributing rollers outwards, and means for rotating the rings.

In testimony wherof I have signed my name to this specification.

HEINRICH GEORG LEICHTWEISS.
